UNITED STATES PATENT OFFICE.

MAURICE J. KARPELES, OF PROVIDENCE, RHODE ISLAND.

DESIGN FOR A DISPLAY-CABINET.

45,718.

Specification for Design.

Patented May 5, 1914.

Application filed January 31, 1914. Serial No. 815,835. Term of patent 7 years.

To all whom it may concern:

Be it known that I, MAURICE J. KARPELES, a citizen of the United States, residing at Providence, in the county of Providence and State of Rhode Island, have invented a new, original, and ornamental Design for Display-Cabinets, of which the following is a specification, reference being had to the accompanying drawing, forming part thereof.

The figure is a perspective view of a display cabinet showing my new design.

I claim:

The ornamental design for a display cabinet, as shown.

MAURICE J. KARPELES.

Witnesses:

E. McCLOSKEY,
M. I. FEENEY.
